UNITED STATES PATENT OFFICE.

PETER F. McCAFFREY, OF SPOKANE, WASHINGTON.

ROOF-FLASHING.

1,244,750.

Specification of Letters Patent. Patented Oct. 30, 1917.

Application filed October 21, 1916. Serial No. 126,952.

To all whom it may concern:

Be it known that I, PETER F. McCAFFREY, a citizen of the United States, residing at Spokane, in the county of Spokane and 5 State of Washington, have invented a new and useful Roof-Flashing, of which the following is a specification.

This invention relates to roof flashings particularly designed for use in connection 10 with vent pipes. It is well known to those skilled in the art that the swaying of a vent pipe soon breaks the connection between the pipe and the ordinary flashing employed, with the result that leaks occur and constant repairing is necessary.

One of the objects of the present invention is to provide a flashing which permits movement of the vent pipe without breaking the connection between the pipe and the 20 flashing or producing leaks.

A further object is to provide simple means for connecting the vent pipe to the flashing and which connection will require practically no attention after having been 25 once applied.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

40 In said drawings:—

Figure 1 is a side elevation of a portion of a vent pipe having the present improvements combined therewith.

Fig. 2 is a vertical section through the 45 flashing and the connection between it and the vent pipe.

Fig. 3 is a plan view of the structure shown in Fig. 1.

Referring to the figures by characters of 50 reference 1 designates a portion of a roof from which extends a frusto-conical flashing 2. A vent pipe 3 is adapted to extend through the flashing, the upper or small end of the flashing fitting snugly about the vent

pipe. After the vent pipe is placed in position, a sleeve 4 having an annularly reduced portion 5 at the center thereof is slipped downwardly onto the pipe. The reduced portion 5 is designed to slidably engage the pipe, while the end portions of 60 the sleeve are concentric with but spaced from the pipe. Thus when the sleeve is moved downwardly on the pipe the lower extremity thereof will receive the upper end of the flashing as shown in Fig. 2 and 65 wedge tightly thereon. After the parts have thus been positioned the space between the pipe and the upper portion of the sleeve 4 is filled with oakum or other packing material indicated at 6 and upon 70 which is poured a layer of lead 7 or the like. Thus the parts are held properly assembled and, obviously, should the vent pipe 3 sway relative to the roof structure 1, no break would occur at the connection between the flashing and the vent pipe but, 75 instead, the lower portion of the sleeve 4 would at all times constitute a water shed and prevent leakage.

What is claimed is:—

The combination with a tubular flashing tapered upwardly, and a vent pipe extending through and fitting snugly within the reduced end of the flashing, of a cylindrical sleeve having a central annular reduced 85 portion the internal diameter of which equals the external diameter of the vent pipe, said reduced portion being curved transversely, thereby to diverge upwardly and downwardly from the vent pipe, one 90 end portion of the sleeve housing and fitting snugly upon the upper portion of the flashing, and a packing within the other end portion of the sleeve and surrounding the vent pipe, the lower portion of the packing 95 being wedged between the vent pipe and the upper portion of the reduced annular portion of the sleeve, thereby to seal the joint between the vent pipe and the sleeve.

In testimony that I claim the foregoing as my own, I have hereto affixed my signature in the presence of two witnesses.

PETER F. McCAFFREY.
